UNITED STATES PATENT OFFICE

SHIRLEY MAXWELL, OF LOS ANGELES, CALIFORNIA

BRASSIERE AND HARNESS

Application filed September 26, 1928. Serial No. 308,449.

This invention relates to a new and improved brassière of simple construction, adapted to cover and support the bust in a natural, youthful position without exerting undue pressure thereon and to a harness permitting said brassière or other brassières to be worn upon the body without discomfort and without exposing said brassières when low-cut gowns are worn.

10 An object of this invention is to provide a brassière adapted to support the bust in a natural, youthful position separately and without forcing them together.

Another object is to provide a brassière 15 adapted to support the bust in a natural position and maintain the bust in said position when the wearer is engaged in strenuous exercise.

Another object is to provide a brassière 20 capable of being worn with low-cut gowns without being exposed by said gowns.

A still further object is to disclose and provide a harness by means of which brassières may be supported upon the body without 25 shifting or slipping.

An object of this invention is to provide a harness whereby brassières may be worn to maintain the busts in a natural youthful position without binding or chafing the 30 wearer.

Other objects and advantages of my invention will become apparent from the following detailed description of one preferred form of my invention shown on the appended 35 drawings in which,

Fig. 1 is a front view of the preferred form of brassière and harness embraced by my invention, showing the position assumed thereby when worn upon the body.

40 Fig. 2 is a three quarter rear view showing the position assumed by the brassière and harness upon the back of the wearer.

Fig. 3 illustrates the pattern of the main pieces from which my improved form of 45 brassière is constructed.

It is well known that with maturity the breasts enlarge and very often change in appearance and structure, becoming rather large, soft and flabby, thereby losing their 50 contour and being displaced from the posi-

tion which they maintain during the youth of a woman. Brassières have been invented which have been provided with pouches adapted to receive the breasts but such brassières do not mould the breasts to a youthful 55 form as they exert a horizontal pressure thereupon, thereby flattening the breasts, crowding them together and actually injuring the tissues.

Furthermore the brassières made heretofore, if so made as to adequately cover the breasts, were simultaneously rather bulky, large and so extensive in area as to prohibit their use with low-cut gowns. Moreover the former brassières did not exert a supporting 60 action upon the breasts and were not attached to the body in such manner as to most effectively support the bust and as a consequence such brassières were inconvenient as they would chafe the wearer, were easily displaced, would slip upon the body, and could not be worn when the wearer was engaged in strenuous exercise.

My improved form of brassière and harness has none of the disadvantages of the 65 prior forms; it may be worn with low cut gowns, will not slip upon the body of the wearer even when the wearer is extremely active and will simultaneously maintain the breasts in position and mould 70 them to a youthful contour. The brassière and harness invented by me exert a pressure and distribute the stresses imposed thereon in such manner upon the body of the wearer that there is substantially no chafing, binding, slipping or undue localized pressure, in fact the wearer does not realize that she is 75 wearing a brassière.

Although the harness or device for maintaining a brassière in position may be used 80 with various forms of brassières having open rear portions, I will describe the harness in combination with my preferred form of uplift brassière.

Referring to Figures 1 and 2 it will be 85 seen that the brassière comprises an upper portion 10 adapted to cover the upper portion of the breasts. Pieces 11 and 12 are attached to the lower edge of portion 10 and are adapted to cover the lower portion of the 90

breasts, the two pieces 11 and 12 being similar and connected together at a seam 13 between the breast receiving pockets formed by this combination of pieces 10, 11 and 12.

5 The upper piece 10 preferably terminates at a substantially vertical seam 14 positioned beneath the armpit of the wearer or slightly in front of said armpit. At the seam 14 the side edges of the upper piece 10 and the 10 lower piece 12 may connect to a side piece 15 running substantially horizontally along the side of the wearer and terminating at the edges of the back of the wearer, as indicated at 16, Fig. 2.

15 Shoulder straps 18 may be attached to the front upper piece 10 at a point 17 and to the rear terminal of side piece 15 at the edge 16, the length of the piece 16 being such (varying with the size of the wearer) as to allow 20 the straps 18 to lie in substantially vertical parallel planes when the brassière is worn. Preferably the shoulder straps 18 are of elastic material.

As shown in Fig. 2 the brassière is provided with an open rear portion between the 25 edges 16 of opposed side pieces 15. This enables the wearer to expose her back in low cut evening gowns without exposing a brassière. The brassière is maintained in this position by the following means:

A separate belt 19 positioned about 2 to 4 inches below the brassière and provided with a rear joining means 20 such as hooks and eyes, snaps, buckle or buttons, is connected 35 by elastic means 21 with the brassière, preferably at the lower rear terminus of the brassière, as at the edge 16. The elastic means 21 are connected to the belt 19 near the joining means 20, thereby causing the elastic connecting means 21 to assume angles with the vertical when the belt 19 is placed upon the body and joined by the means 20. This causes a pull to be exerted upon the rear lower edges of the brassière downwardly and 40 toward the center assuring a close fit. The elastic connecting means 21 may be continuations of shoulder straps 18. The belt 19 is 45 preferably of elastic material.

The length of the elastic members 21 connecting a brassière with the belt 19 may vary in accordance with the height of the wearer, the belt 19 being worn in a natural position at the waistline of the wearer. The lower ends of the connecting pieces 21 are preferably joined to the belt 19 near the clasp or joining means 20 so that the elastics 21 are stretched toward the small of the back when the belt is fastened by means 20.

In Fig. 3, the pattern is shown from which 50 the various pieces may be cut. Only one half of the upper piece 10 is shown as the material may be folded upon the center line 22 and both sides cut simultaneously. The length of the material preferably runs from 55 right to left as indicated. The side edge 29

is preferably small while the upper edges 31 and 32 are cut on concave arcs toward the point 17 to which the shoulder strap is attached. The lower edge of the piece 10 may assume a substantially parabolic curve or be 60 provided with substantially straight edge portions 23 and 23 joined by a curved tip 24.

The lower portion 11 may be provided with a substantially parabolic upper edge comprising edges 26 and 27 and a curved tip 25. 70 Edges 23, 24 and 23 of the upper portion 10 are connected to edges 26, 25 and 27 respectively of the lower portion 11, thereby forming the seam 33, (Fig. 1) which seam when the brassière is upon the body assumes a substantially horizontal position passing directly over the nipples. The lower edge 28 of the lower portion 11 may also be cut on an arc as shown. The edges 13 and 30 may be straight but inclined to each other so that the 80 edges 13 of adjoining lower portions form the vertical seam 13 (Fig. 1) while the edge 30 is joined to edge 14 of piece 15 forming a 85 vertical seam also.

The edge 29 of piece 11 is also attached 90 to piece 15 at the edge 14. Preferably the material from which pieces 11 and 12 are cut runs in length vertically as indicated in Fig. 3, edges 26, 27, 30 and 13 being cut on a bias while edge 28 or the tip 25 is not.

95 It will be seen by the above construction the brassière is retained in position upon the body and the breasts supported in a predetermined manner without binding. The articulation of the arms is not interfered with and the breathing of the wearer is not restrained.

100 My invention is not limited to the precise construction and combination described above however, as the harness may be used with any type of brassière having an open rear portion, and all modifications and changes coming within the following claim 105 are embraced thereby.

I claim:

A garment comprising in combination a 110 brassière incompletely encircling the body and terminating at the sides of the back whereby said brassière is adapted to support and mold the breasts without restricting chest expansion, shoulder straps carried by 115 said brassière, a separate narrow elastic belt provided with rear joining means, and elastic connectors extending from the extremities of the rear end portions of the brassière, diagonally downward and rearward to 120 and connected with said belt on opposite sides of said joining means leaving an unrestricted space between the rear end portions of the brassière so as not to expose any portion of the garment between said shoulder straps 125 above said belt.

Signed at Los Angeles, California, this 19 day of September, 1928.

SHIRLEY MAXWELL. 130
